UNITED STATES PATENT OFFICE.

PHILIP H. HOLMES, OF GARDINER, MAINE.

WOOD FIBER FOR PAPER-PULPS AND PROCESS AND MACHINE FOR PRODUCING THE WOOD FIBER.

SPECIFICATION forming part of Letters Patent No. 228,899, dated June 15, 1880.

Application filed May 24, 1880. (No model.)

To all whom it may concern:

Be it known that I, PHILIP H. HOLMES, of Gardiner, in the county of Kennebec and State of Maine, have invented certain new and useful Improvements in Wood Fiber for Paper-Pulps and the Process and Machine for Producing the Wood Fiber; and I do hereby declare the following to be a full, clear, and exact description of the invention, such as will enable others skilled in the art to which it pertains to make and use it, reference being had to the accompanying drawings, which form part of this specification.

My invention relates to an improvement in wood fiber for paper-pulp and the process and machine for producing the wood fiber.

Heretofore wood pulp has ordinarily been made by forcing blocks of wood against the face of a grindstone running in water, the wooden blocks being arranged so as to be ground transversely to the grain of the wood, or at right angles to the length of the fiber. This process is objectionable for various reasons, among which are the following: The fibers being severed at right angles to their length results in a product composed of very short and finely divided particles of wood, which latter being made into paper has comparatively little strength to resist being torn and severed when employed for ordinary uses. Especially is this true when light paper is made of the ordinary wood pulp.

Again, in the grinding process it is necessary to perform the operation under water to prevent the wood from being burned or charred, and hence the ordinary wood pulp is impregnated with water, which adds very materially to its weight and cost of transportation. The consumer is obliged to keep the fiber impregnated with water, because when once wet it cannot be dried without causing the mass to adhere together and form itself into lumps, so that it is practically impossible to separate the ground fiber after it has been dried. The necessity for keeping the fiber wet until used by the manufacturer calls for an additional outlay of time, expense, and risk, as the mass is liable to freeze and also to mildew.

Again, machines have been constructed for subjecting blocks of wood to the action of grindstones or cylinders, the fiber being sev-

ered diagonally to its length; but this process is subject to all the objectionable features above noted, as the grindstones must be run in water, thereby producing finely-divided particles of ground wood impregnated with water.

Further, machines for making wood pulp have been provided with revolving and reciprocating saws, cutters, and grinding-surfaces, ordinarily arranged to operate transversely to the length of the fiber and separate it from the block by a grinding, scraping, or rasping action. Such machines have been found defective for the reason that the fiber is either severed into very short or minute particles, rendering it unsuitable for the manufacture of strong and durable paper, or when the revolving cutters or grinding-surfaces operate in line with the length of the fiber the latter is clipped off from the block in varying sizes and lengths, and must be beaten for a great length of time to reduce it to the proper degree of fineness before it is suitable for use, the beating process operating to break up and destroy the length of the fiber.

The prime object of my invention is to produce wood fiber of any degree of fineness and of the desired length, the fiber to be perfectly light and dry, and thus adapted for economical shipment and storage, and also suitable for producing paper of either light or heavy stock which shall be of great strength and toughness; and with these ends in view my invention consists, first, as a new article of manufacture, of wood fiber for paper-pulp, the fiber being cut from the block in any desired lengths and degree of fineness and prepared for shipment and use in a dry condition.

My invention further consists in the process of making wood fiber for paper-pulp, consisting, essentially, in severing the fiber from revolving pieces or blocks of wood by stationary knives or cutters arranged to operate in line with the grain of the wood or the length of the fiber.

My invention further consists in a machine for producing wood fiber for paper-pulp, consisting, essentially, in the combination, with a suitable mandrel and chuck for holding and rotating a wooden block, of a series of stationary knives, cutters, or chisels arranged to sever the fiber from the block.

My invention further consists in the combination, with a suitable mandrel and chuck for holding and rotating a block or piece of wood, of two series of knives, cutters, or chisels arranged to sever the fiber from opposite sides of the block, the cutters of one series intersecting those of the other series.

My invention further consists in certain other details in construction and combinations of parts, as will hereinafter be described, and pointed out in the claims.

In the accompanying drawings, Figure 1 is a plan view of one form of machine embodying my invention. Fig. 2 is a view in side elevation, and Fig. 3 is an end view.

A represents the bed of the machine. B is the head-stock, and C is the tail-stock, the latter being furnished with the mandrel a. A belt-pulley, D, is secured to the live-spindle E, the latter having a chuck, F, secured thereto.

G represents a block of wood secured between the chuck F and mandrel a, and adapted to be revolved by the live-spindle.

On opposite sides of the bed or frame A are placed the sliding blocks or rests G' G², each having a series of cutters or chisels, H, secured thereto, the cutters of one series being arranged to intersect the cutters of the other series, so that the cutters of one series will operate on the block of wood at one side and sever a portion of the fiber from the block, while the cutters of the other series will remove the remaining portion.

Cutters or chisels H are made very sharp and secured at the angle shown in the drawings or any other suitable angle, and when the machine is in operation will operate to sever the fiber in lengths equal to the width of the cutters, the fineness of the fibers being regulated according to the rapidity with which the cutters are fed toward the block of wood and the velocity with which the latter is revolved.

The knives or cutters may be automatically fed toward the block of wood as follows: A gear-wheel, I, is keyed to the end of the spindle E, and meshes with gear-wheel J, keyed to the end of worm-shaft K. A worm-gear, L, on shaft K engages with and rotates a worm-gear, M, secured to the screw-shaft N, the latter being provided with right and left hand screw-threads b c. The right-hand screw-thread engages in corresponding screw-threads cut in the lower end of the adjustable rest G' and the left-hand screw-thread in the rest G². Hence by revolving the screw-shaft N the sliding blocks or rests G' G² are drawn toward each other, and thus serve to automatically feed the cutters to their work.

By reversing the motion of shaft N the rests are separated for the insertion of another block of wood. The opposite ends of the screw-shaft are provided with handles O O', to allow the cutters or chisels to be adjusted by hand. Bearing P of the screw-shaft is preferably

made vertically adjustable, to enable the worm-gears to be thrown out of gear whenever desired, in order to allow the cutters to be fed by hand.

In practice the machine may be operated by cone-pulley gearing and automatically regulate the feed, as the cutters need to be fed more rapidly after the block has been partly cut away than at the outset. By employing wide cutters and feeding them slowly, at the same time revolving the block at a comparative high rate of speed, I am enabled to produce very fine and long fibers, suitable for producing paper stock of light weight and of great strength and tenacity. For heavy paper the cutters may be made narrower and fed against the block with greater rapidity.

It will be observed that in my improved process for producing wood fiber the fiber is not ground, rasped, or sawed from the block, and hence is not impregnated with water, and, further, does not vary in size, as is the case in all ordinary processes. The knives or cutters, being stationary and slightly impinging against the rapidly-revolving block of wood, operate to neatly sever the fiber from the block, thereby producing a perfectly dry and light mass of fiber, which may be transported at slight cost, and is in condition for storage until ready for use without danger of becoming impaired by heat, cold, or moisture.

In all cases where wooden blocks are reduced to paper-pulp by grinding, rasping, or sawing, a large percentage of the stock is reduced to dust, which is unfit for use, while the remaining portion varies in the size of its particles.

My improved wood fiber is of even size and length, and when manufactured into paper produces a very superior article.

Gear-wheels I and J are adapted to be readily removed from the shafts and replaced by gears of different relative diameters, to insure any desired rapidity of feed of the cutters or knives.

While I have described one form of machine for producing the desired result, I am aware that the machine will admit of many variations in its construction and arrangement of parts and still effect the object hereinbefore set forth; and hence I would have it understood that I do not restrict myself to the peculiar construction and combinations of parts shown and described; but,

Having fully described my invention, what I claim as new, and desire to secure by Letters Patent, is—

1. As a new article of manufacture, dry wood fiber, the fiber of each grade being practically uniform in length and size, and severed transversely to its length, substantially as set forth.

2. An improvement in the art of making wood fiber for paper-pulp, the same consisting, essentially, in cutting the fiber from a revolving block of wood by means of stationary

knives or cutters arranged to operate in line with the grain of the wood or the length of the fiber, substantially as set forth.

3. A machine for making wood fiber for paper-pulp, consisting, essentially, in the combination, with suitable devices for holding and revolving a block of wood, of a series of stationary knives, cutters, or chisels arranged to cut the fiber from the block, substantially as set forth.

4. In a machine for producing wood fiber for paper-pulp, the combination, with suitable devices for holding and revolving a block of wood, of two series of knives, cutters, or chisels arranged to cut the fiber from opposite sides of the block, the cutters of one series intersecting those of the other, substantially as set forth.

5. In a machine for producing wood fiber for paper-pulp, the combination, with suitable devices for holding and revolving a block of wood, of one or more series of knives, cutters, or chisels arranged to cut the fibers from the block in the line of their length, and mechanism for automatically feeding said cutters against the block of wood, substantially as set forth.

In testimony that I claim the foregoing I have hereunto set my hand this 24th day of May, 1880.

PHILIP H. HOLMES.
